MOISTENER

Otto Lehre, Springfield, N.J., assignor to Sterling Plastics Co., Union, N.J., a corporation of New Jersey

Application June 13, 1957, Serial No. 665,519

2 Claims. (Cl. 15—136)

This invention relates to moisteners for stamps, labels, and the like, and particularly to a moistener in which the body of absorbent material which applies liquid to the desired objects is firmly secured in proper position relative to the source of liquid.

One of the objects of my invention is to provide a new and improved moistener which is self-contained and economical to manufacture.

Another object of my invention is to provide a moistener which is preferable in many cases to the moisteners heretofore used because it is easily used with a minimum of undesirable liquid leakage.

It is also an object of my invention to provide a moistener constructed by the mere assembly of a small number of cooperating parts, each of which is an integrally molded piece of a thermoplastic resin, such as a suitable polystyrene or polyethylene plastic.

Still another object of my invention is to provide a moistener which includes new and improved securing means for the body of absorbent material which applies liquid to the objects to be moistened.

The moistener provided according to this invention includes a container for holding a quantity of liquid, a closure for said container having an orifice therein communicating with the space in said container, said orifice providing for a limited flow of the liquid therethrough, a body of absorbent material overlying said closure to receive liquid from said orifice, means peripherally binding said body of absorbent material over said closure while exposing a substantial portion of said body for use to apply liquid absorbed therein to objects contacted thereby, said closure having an upwardly directed ledge around the same and said binding means comprising a ring fitted over said closure having a ledge spaced inwardly and directed downwardly from the top of said ring, said body being confined between said ledges, and cooperating means on said ring and said closure for locking said ring to said closure.

According to further features of the invention, the ledges are formed as integral parts of the closure and the ring, and each part of the device except the absorbent body is made as a single molded piece of a suitable thermoplastic resin, such as a polystyrene or a polyethylene resin.

The foregoing and other objects, features and advantages hereof will become apparent from the following detailed description of an illustrative embodiment, while the new features of construction and operation which I claim as my invention will be set forth more particularly in the appended claims. The detailed description refers to the accompanying drawings which form a part hereof and in which:

Fig. 1 is an exploded view of the moistener of the invention;

Fig. 2 is a cross-sectional view of the moistener of the invention with all of the parts in assembled relation; and

2

Fig. 3 is a bottom plan view of the closure assembly utilized in the moistener of the invention.

As appears from the drawings, the moistener of the invention has a container 10, preferably including a neck 5 11 having external threading 12 thereon. In a preferred form, the container, the neck and the threading are constructed as an integral unit of a flexible resin, such as a suitable polyethylene plastic. In this form the container is of the squeeze bottle type wherein the sides of 10 the container may be flexed inwardly to force the liquid inside of the container out through the opening in neck 11.

A closure member 13, having a neck receiving portion 14 which is internally threaded, as at 15, is provided for closing the opening in the neck 11. The top 16 of the head of the closure member 13 has an orifice 17 which communicates with the opening in neck 11 so that a small amount of liquid may pass therethrough. If, as in the form shown in the drawings, the container is formed of a flexible material the size of the orifice is such that liquid will not flow therethrough until the container is flexed inwardly, thereby avoiding undesirable leakage when the device is inverted or inadvertently dropped or upset. Also formed as a part of the closure member is a continuous circular lip 18 which is directed upwardly from the peripheral edge of top 16.

A knurled ring 19, having a larger diameter than the rest of the closure member and integrally connected thereto by ribs or webs 20 and 21, may be provided for 30 facilitating the removal of the closure member from the neck. This construction provides ledges 22 above the knurled rim for engaging corresponding portions of the locking ring, in a manner to be described later. As is best seen in Figs. 2 and 3 all of the above described 35 parts of the closure member are formed in an integral unit, preferably formed of a suitable thermoplastic or thermosetting resin. In order to decrease the cost of forming and to decrease the weight of the closure member, said closure member may be advantageously formed 40 with open portions such as at 23 and 24 without decreasing its strength and durability.

A pad of absorbent material 25, such as a natural or synthetic sponge material, preferably having the shape of a circular disc or pad, is positioned over the closure member 13, in communication with orifice 17, so that it 45 may absorb liquid flowing through said orifice.

In order to secure said pad of absorbent material to 50 said closure member while exposing a substantial portion of said pad for use to apply the liquid absorbed therein to objects contacted thereby, a locking member or ring 26 is provided. As shown in Figs. 1 and 2, this ring may be tapered outwardly toward its bottom edge. The ring has a top flange portion 27, which may be tapered upwardly and which terminates in a downwardly extending continuous circular lip 28 spaced inwardly from the top of the body of the ring. This lip cooperates with lip 18 to confine pad 25 so that the pad is securely held in position while exposing a substantial portion of the pad for use as a moistener, as best seen in Fig. 2. The tight binding of peripheral portions of the absorbent sponge pad 25 between the downwardly directed lip 28 on ring 26 and the upwardly directed lip 18 on member 13 insures a firm holding of the absorbent pad in 60 position to receive liquid from orifice 17, and forms a substantially liquid tight seal about the periphery of the pad 25.

Tabs 29 on the inner surface of ring 26 are adapted 65 to snap over and engage beneath the ledges 22 of closure member 13 in order to firmly lock ring 26 to the closure member. All of the parts of the ring are molded in an integral unit, preferably of a flexible plastic material such as polyethylene.

The parts of the moistener, the container, the closure member and the ring, are each formed by filling a mold cavity with a suitable resin while the resin is in a molten state and then cooling the molded resin. The mold cavities are shaped so that each molded piece is formed integrally with all of its structural elements which cooperate with other parts of the moistener. Thus, the container is formed with an integral neck 11 having integral threading 12 thereon; the closure member is formed with integral lip 18, knurled ring 19, webs 20 and 21 and ledges 22; and ring 26 is formed integrally with flange 27 having lip 28 thereon, and tabs 29.

The moistener of the invention is readily assembled by placing the pad of absorbent material over the closure member, pressing the ring 26 downwardly over the pad of absorbent material until tabs 29 on the ring snap under ledges 22 on the closure member, and then screwing the moistening assembly onto container 10. This manner of assembly is economical and can be accomplished with a minimum number of operations.

It will be evident that the invention provides a moistener which is economical to construct and is readily assembled, which is leakproof, portable, and durable and which is particularly valuable for moistening stamps, labels and the like.

I claim:

1. A closure device for a liquid applying container comprising a hollow body member having means for attachment thereof to the neck of the container, said body member including a head having an orifice therethrough overlying the neck opening of the container and a skirt portion depending from the periphery of said head, said head having a continuous lip directed upwardly from its upper surface near the periphery thereof; a pad of absorbent material laid on said head and extending marginally over said lip, a binding ring formed to surround said head and having a top opening to expose said pad, said ring having a downwardly directed continuous lip near the margin of said opening; said body member being recessed near the lower part of said skirt to provide downwardly facing ledges spaced about said member; and inwardly directed tabs on the lower part of said ring to engage said ledges; said ring being formed so that when it is force fitted over said body member said tabs resiliently lock it in place when its lip compresses the margin of said pad against the lip of said head so as to hold the ring and the pad securely on said head and confine the

liquid to the area of said pad within said opening; the closure device being removable from the container as a unit for refilling of the container and said ring being independently removable from said body member so that the pad of absorbent material can be replaced.

2. A closure device for a liquid applying container comprising a hollow body member having means for attachment thereof to the neck of the container, said body member including a head having an orifice therethrough overlying the neck opening of the container and a skirt portion depending from the periphery of said head, said head having a continuous lip directed upwardly from its upper surface near the periphery thereof; a pad of absorbent material laid on said head and extending marginally over said lip; a binding ring formed to surround said head and having a top opening to expose said pad, said binding ring having a downwardly directed continuous lip near the margin of said opening; said body member being recessed near the lower part of said skirt to provide downwardly facing ledges spaced about said member; inwardly directed tabs on the lower part of said ring to engage said ledges; said binding ring being formed so that when it is force fitted over said body member said tabs resiliently lock it in place when its lip compresses the margin of said pad against the lip of said head so as to hold the ring and the pad securely on said head and confine the liquid to the area of said pad within said opening; the closure device being removable from the container as a unit for refilling of the container and said binding ring being independently removable from said body member so that the pad of absorbent material can be replaced; said body member further comprising a knurled ring disposed below said binding ring for facilitating the removal of the closure device as a unit and a plurality of webs located between said ledges and connecting said knurled ring with said skirt.
